UNITED STATES PATENT OFFICE.

FREDERICK W. DUQUETTE, OF ST. PAUL, MINNESOTA.

ASH-RECEIVING ATTACHMENT FOR CIGARS AND ANALOGOUS SMOKES.

Application filed August 17, 1925. Serial No. 50,737.

To all whom it may concern:

Be it known that I, FREDERICK W. DUQUETTE, a citizen of the United States, residing at St. Paul, in the county of Ramsey and State of Minnesota, have invented certain new and useful Improvements in Ash-Receiving Attachments for Cigars and Analogous Smokes; and I do declare the following to be a full, clear, and exact description 10 of the invention, such as will enable others skilled in the art to which it appertains to make and use the same.

My invention relates to improvements in devices which are applicable to the ends 15 of cigars or other smokes, for the purpose of receiving the ashes as the latter are formed, preventing them from falling onto the smoker's clothing, the floor, etc.

The principal object of the invention is 20 to provide a device of the character set forth which, while being extremely simple and inexpensive, will be efficient and very desirable.

With the foregoing in view, the invention 25 resides in the novel subject matter herein-after described and claimed, the description being supplemented by the accompanying drawing.

Figure 1 is a side elevation of the invention upon a cigar.

Figure 2 is a longitudinal sectional view.

Figures 3 and 4 are transverse sections on lines 3—3 and 4—4 of Fig. 1.

Figure 5 is a plan view of the sheet metal 35 blank from which a portion of the device is formed.

Figure 6 is a longitudinal sectional view showing a different form of construction.

In the form of the invention disclosed in 40 Figs. 1 to 5, the device includes a frame F composed of spaced cigar-encircling bands 1 and 2 connected by longitudinal bars 3 which are spaced apart circumferentially, said bars projecting beyond the band 2 and 45 having their projecting ends 4 curved inwardly into overlapping relation, to provide a closed end for the frame, the opposite end of this frame being open.

A cylindrical screen 5 is disposed in the 50 frame F and is formed with a closed end 6 which contacts with the closed end of said frame. A knob 7 contacts with the outer side of this closed frame end, and in the present showing, small nails 8 pass through 55 the screen end 6, through a washer 9 contacting with said screen end and are driven

into the knob 7 so as to secure these parts together. These nails also preferably pass through the inwardly curved bar ends 4.

A straight, wire stem 10 is disposed longitudinally in the openwork thimble formed by the construction above described, one end of said stem passing through the parts 4, 6 and 9, and being driven into or otherwise embedded in the knob 7. By grasping the 65 knob 7, the stem 10 may be forced into the cigar to effectively hold the device in place, and as the cigar is consumed, said stem may be used to adjust the ash receiver inwardly upon the same, so as to collect all ashes as 70 they are formed. The knob 7 is preferably formed of heat-insulating material, so that there is no danger of burning the fingers when adjusting the device.

To assist in securing the ash receiver upon 75 the cigar and to prevent leakage of ashes from the open end of said receiver, an elastic band 11 surrounds the latter and projects beyond the same, the projecting portion of the band being self-contracting to a 80 diameter smaller than the diameter of the thimble or ash receiver, so as to tightly embrace the cigar.

In the preferred manner of constructing 85 the device shown in Figs. 1 to 4, the frame F is formed of a single sheet metal blank, (preferably aluminum). This blank is shown in Fig. 5, and the portions 1', 2', 3' and 4' of this figure are the parts of the blank which form the parts 1, 2, 3 and 4, 90 when said blank is bent into the proper shape. Flanges 12 are formed on the opposite ends of the blank, said flanges being bent and interhooked to secure the blank in frame-forming position, as will be clear from 95 Fig. 3 and Fig. 5.

In the form of construction disclosed in 100 Fig. 6, an ash receiver or thimble is shown, comprising a sheet metal cup 13 perforated as at 14, longitudinal bars 15 projecting from the edge of the cup and connected by a ring 16, an elastic band 17 carried by this ring, and a screen 18, the latter being disposed within the edge portion of the cup 13, the bars 15 and the ring 16, although it need 105 not extend over the perforations of the cup.

At the outer side of this cup, I have shown a knob 19 and a stem 20 is connected with this knob, said stem preferably having a shoulder 21 which abuts the inner side of 110 the cup.

The form of construction last described is

equally as advantageous as the construction first explained. Any form of the invention is simple and inexpensive, yet is a great asset to the cigar smoker, and it will be understood that the scope of my invention is of course such as to protect the latter made in any desired size, whether used upon cigars, cigarettes or other analogous smokes.

I claim:

10. 1. An ash receiving attachment for a cigar or analogous smoke, comprising a foraminous thimble having a central opening in its closed end, a knob secured in contact with the outer side of said closed end, and an elongated wire stem disposed longitudinally in said thimble to penetrate the cigar, one end of said stem passing through said opening and being embedded in said knob.
20. 2. An ash receiving attachment for a cigar or analogous smoke, comprising a foraminous thimble and an elastic band secured to said thimble and extending around the open end thereof, said band having a portion projecting beyond said open end of the thimble and said projecting portion being self-contracting to a diameter smaller than the diameter of the thimble to yieldably engage a cigar.
30. 3. An ash receiving attachment for a cigar or analogous smoke, comprising a frame consisting of spaced cigar-encircling rings con-

nected by circumferentially spaced parallel bars, said bars projecting beyond one of said rings and having their ends curved inwardly into overlapping relation to form a closed end for the frame, a cylindrical screen within the frame having a closed end contacting with the closed end of the frame, a knob contacting with the outer side of said closed end of the frame, and means securing the closed ends of the screen and frame to said knob.

4. An ash receiving attachment for a cigar or analogous smoke, comprising a frame consisting of spaced cigar-encircling rings connected by circumferentially spaced parallel bars, said bars projecting beyond one of said rings and having their ends curved inwardly into overlapping relation to form a closed end for the frame, a cylindrical screen within the frame having a closed end contacting with the closed end of the frame, a knob contacting with the outer side of said closed end of the frame, a wire stem disposed longitudinally in the screen to penetrate the cigar, one end of said stem passing through said inwardly curved bar ends and into the knob, and means securing said bar ends and the closed end of the screen to said knob.

In testimony whereof I have hereunto affixed my signature.

FREDERICK W. DUQUETTE.
